UNITED STATES PATENT OFFICE.

JNO. W. BOWERS, OF BROOKLINE, MASSACHUSETTS.

IMPROVEMENT IN ORNAMENTAL PAINTING ON GLASS, &c.

Specification forming part of Letters Patent No. 8,651, dated January 13, 1852.

To all whom it may concern:

Be it known that I, JOHN W. BOWERS, of Brookline, in the county of Norfolk and State of Massachusetts, have invented a new and useful Method, Art, or Process of Ornamenting Glass or other Transparent Medium; and I do hereby declare that the same is fully described and represented in the following specification.

My process imparts to a painting on glass an appearance very much like those figures which are executed on wood or papier-maché, and which are more or less or in part made up of pieces of mother-of-pearl let into the wood. The paintings or figures produced by my said method have very beautiful properties of reflecting light—such as are often exhibited by silvered, prismatic, or crystalline surfaces.

In order that the principle of my invention may be understood, I will proceed to explain the application of the same to a plate of glass.

A bunch of flowers or any ornamental figure to be painted is first to be outlined on the back side or surface of the sheet or plate of glass, and all such parts as compose the figure are to be colored in transparent colors of various shades and lines, as may suit the taste of the painter, the background being next laid on in an opaque color, and so as to extend up to the outer boundaries of the various parts of the design. This having been done, or the picture prepared in any other suitable manner so as to exhibit more or less transparency of color, I take silver-foil or other proper metallic leaf-foil and crush or double it up or compress it together in such manner that when it is spread out or opened its whole surface shall present irregular doublings, crossing one another in various directions, and so as to impart to the piece of foil an appearance of irregular crystallization, or, instead of such a method of producing the double or proper figured appearance of the foil, any other more suitable or convenient process of effecting the

same may be employed. The foil so prepared I place or lay on and over the colored figure on the glass and secure it in place by a light glutinous size or by any other suitable means, finally protecting the whole by a backing of paper or any other proper material pasted or otherwise fixed over the same.

When I desire to produce the effect on a transparent medium resting on a covering or opaque medium—such as wood or papier-maché, for instance—I first cover the surface to be ornamented with a varnished or other proper background or prepare the background by any desirable means. I next draw out or outline upon such background the figure to be produced. I next lay over such parts of it as are to have the sparkling metallized appearance the corrugated or crimped foil cut up into the necessary shapes. I next paint on the foil with transparent or semi-transparent colors the light parts of the figure, the darker shades or coloring being effected by more opaque colors or matters. I next put the plate of glass or the transparent medium or one or more coats of varnish or japanning over the whole, and by such means I produce a figure or figures having, when exposed to strong light, not only a metallic luster, but a most beautiful sparkling or scintillated appearance.

What I claim as my improvement in ornamenting surfaces consists in—

Combining with the process of painting and ornamenting by metallic foil that of corrugating or crimping the foil so as to impart to the figure or figures a power of reflecting light so as to produce the sparkling scintillated appearance, as specified.

In testimony whereof I have hereto set my signature this 27th day of October, A. D. 1851.

JOHN W. BOWERS.
